UNITED STATES PATENT OFFICE.

MARTIN DAVID WISCHKER, OF RIGA, RUSSIA.

SCROLL-SAWING MACHINE.

SPECIFICATION forming part of Letters Patent No. 361,800, dated April 26, 1887.

Application filed June 17, 1886. Serial No. 205,391. (No model.) Patented in Belgium May 1, 1886, No. 72,954; in England May 3, 1886, No. 5,997; in Sweden May 6, 1886, No. 544; in Norway May 22, 1886, No. 150; in Denmark August 20, 1886; in Austria-Hungary October 15, 1886, and in France January 7, 1887.]

To all whom it may concern:

Be it known that I, MARTIN DAVID WISCHKER, a subject of the Emperor of Russia, residing at the city of Riga, in the Empire of Russia, have invented certain new and useful Improvements in Sawing-Machines, (for which I have obtained Letters Patent in Belgium, No. 72,954, dated May 1, 1886; in Denmark, dated August 20, 1886; in Norway, No. 150, dated May 22, 1886; in Sweden, No. 544, dated May 6, 1886; in England, No. 5,997, dated May 3, 1886; in Austria-Hungary, dated October 15, 1886, and in France, dated January 7, 1887,) of which the following is a specification.

15 The object of my invention is to provide a new and improved sawing-machine, in which a short saw-blade can be held and guided in such a manner that it can be subjected to tension and compression strain without bending or doubling.

20 The invention consists in the combination, with a holder for the saw-blade, of mechanism for reciprocating the holder, a vertically-adjustable sawing-table, on which the board to be sawed is placed, and a guide-slot in said table.

25 In the accompanying drawings, Figure 1 is a cross-sectional view of my improved sawing-machine, parts being broken out. Fig. 2 is a similar sectional view, showing other parts. Fig. 3 is a side view of a sawing-machine. Fig. 4 is a plan view of the table; and Fig. 5 is a sectional view on the line A B, Fig. 2.

30 Similar letters of reference indicate corresponding parts.

35 On the end of the arm C two jaws, a' a'' , are clamped and held by means of suitable screws, the jaw a' projecting some distance below the lower end of the jaw a'' . The jaw a'' is provided 40 in its inner surface with a recess, in which the vertically-reciprocating rod a is guided, said rod being provided at its upper end with a cross-piece, D, having a slot or recess, E, and a cam portion, b. A pin, e, projects from the 45 end of a disk, d, mounted on a shaft, e, journaled in an upwardly-projecting part of the arm C, which pin can pass into the slot E of the cross-piece D. The saw-blade s is guided in the groove a' in the inner side of the jaw a' , and 50 said blade is provided near its upper end with

a laterally-projecting lug, s' , which fits into a corresponding recess of the reciprocating rod a , whereby the saw-blade and rod are coupled. The shaft e may be revolved by hand or machine power, as desired. The sawing-table f 55 is provided at its center with a steel plate, f' , provided with a circular opening for the sawdust, and a notch, f'' , in the edge of said opening for the purpose of guiding the lower edge of the saw-blade s . The table f is secured on 60 a vertically-movable support, F, guided in a yoke, G, secured to the under side of the frame. Through the lower end of the yoke a screw, h , is screwed, the upper end of which is mounted to turn in part of the support F, a hand-wheel, 65 h , being secured to the lower end of the screw. By turning the hand-wheel the table f is moved up or down. The support F is provided with a groove, f^2 , for carrying off the sawdust. The table f is so adjusted that the 70 distance between the lower end of the jaw a' and the top of the table is about equal to the thickness of the piece of wood to be sawed. The upper end of the saw-blade is guided in the groove a'' and the lower end in the notch f'' , 75 and the jaw a' is of such a length that the free end of the blade is always in the notch f'' , so that the saw is guided and cannot bend or double over, as the space between the lower end of the notch of the table f is too small to admit 80 of such doubling or bending. A short saw-blade may thus be used advantageously for the same purpose for which a band-saw or jig-saw held at the top and bottom are now used. The saw is fastened and unfastened easily and rapidly, and is held securely.

85 When the disk d is revolved in the direction of the arrow m , Fig. 2, the pin e enters the notch or recess E of the cross-piece D and the bar a is reciprocated. When the disk d is rotated in the inverse direction of the arrow m' , the pin e slides along the bottom edge of the cam-part b and raises the same, whereby the rod a is raised, as shown in Fig. 2, so as to 90 permit the removing of the saw-blade.

95 Having thus described my invention, I claim as new and desire to secure by Letters Patent—

1. In a sawing-machine, the combination of two elongated jaws, one of which has a groove for guiding the saw and the other a recess for 100

the saw-bar, a vertically-reciprocating bar mounted to slide in said recess, and a saw-blade connected to said bar and adapted to slide in said groove, substantially as described.

5. 2. In a sawing-machine, the combination of two elongated jaws, one of which extends below the other, the longer jaw having a guide-groove for the saw-blade and the shorter jaw a recess for the saw-bar, a vertically-reciprocating saw-bar mounted to slide in said recess, and a saw-blade connected to said bar and adapted to slide in said groove, substantially as described.

3. In a sawing-machine, the combination of 15 two elongated jaws, one of which has a groove for guiding the saw-blade and the other a recess for the saw-bar, a vertically-reciprocating saw-bar mounted to slide in said recess, a saw-blade connected to said bar and adapted to 20 slide in said groove, and a vertically-adjustable table below said jaws, said table being provided with a notch for guiding the free end of the saw-blade.

4. In a sawing-machine, the combination, 25 with a box having a longitudinal groove for guiding the bar, of a reciprocating bar within the box, a notch in said bar for receiving a projection of the saw-blade, a frame adapted

to be moved toward and from the said box by means of a screw, which frame has an aperture 30 or channel for carrying off the sawdust, and a table having a notch for guiding the free end of the saw, the table being on said frame, substantially as shown and described.

5. In a sawing-machine, the combination, 35 with the arm C, of the jaws a' a², the former having a guide-groove, a⁰, the saw-blade s, having the lug s', and the reciprocating bar a, having a notch for receiving the lug s', substantially as shown and described. 40

6. In a sawing-machine, the combination, with a box for guiding the blade, of a reciprocating bar in said box, the cross-piece D on said bar, which cross-piece has a slot or recess, E, and a cam part, b, the end disk, d, mounted 45 on a shaft, e, and provided with the pin c, and a table having a notch for guiding the free end of the saw-blade, substantially as shown and described.

In testimony whereof I have signed my name 50 to this specification in the presence of two subscribing witnesses.

MARTIN DAVID WISCHKER.
